UNITED STATES PATENT OFFICE.

JAMES A. BROWNFIELD, OF COVINGTON, KENTUCKY.

JOINT.

1,171,589.

Specification of Letters Patent. Patented Feb. 15, 1916.

Application filed May 3, 1915. Serial No. 25,369.

To all whom it may concern:

Be it known that I, JAMES A. BROWNFIELD, a citizen of the United States of America, and resident of Covington, county 5 of Kenton, State of Kentucky, have invented certain new and useful Improvements in Joints, of which the following is a specification.

This invention relates to improvements in joints for water closet seats and has for an 10 object to produce a joint which eliminates the use of plugs or bolts for drawing its members.

A further object is to produce a joint 15 which will allow a water closet seat to be built up of short pieces comprising the odds and ends of the shop.

A further object is to produce a joint 20 which will not warp and pull apart.

These and other objects are attained in the joint described in the following specification and illustrated in the accompanying drawings in which:

Figure 1 is a perspective view of a seat 25 employing the joint embodying my invention. Fig. 2 is a plan view of the seat embodying my invention, but showing it in the process of construction. Fig. 3 is a sectional view taken on the line 3—3 of Fig. 1 and 30 upon an enlarged scale and illustrating the construction of the joint. Fig. 4 is a fragmental perspective view showing the manner in which the joint formations are simultaneously made on the pieces to be joined.

The seat constructed with joints embodying my invention consists of a back piece 4, side pieces 5 and 6, a front piece 7, and locking blocks 8 and 9 adapted to enter between 35 the front piece 7, and the side pieces 5 and 6.

The joint formed between each of the pieces is constructed in the manner illustrated in Fig. 3 and consists in producing the same formation on both pieces forming the joint, the formation being such that when 40 one of the pieces is reversed, the formation on the pieces will interlock closely with one another.

The joint embodying my invention is 45 illustrated in Fig. 3 and in referring to this joint I have referred to only one of the pieces forming the joint, the reference characters being applied to the piece 5. The joint consists in forming on each piece, an undercut eccentric tongue 10, which is offset somewhat from the center and which is provided with a straight edge 11 and an in-

clined edge 12. Adjacent to the straight edge is formed a tongue 13 which is provided with an inclined edge 14 extending outwardly to meet the edge 15 forming one 60 face of the piece. On the opposite side of the undercut tongue 10, and spaced away from its inclined edge 12, is a tongue 16 having an edge 17 parallel with its edge 18 which forms the opposite face of the piece. 65 Joining these parallel edges an inclined edge 19 parallel to the edge 14 of the tongue 13 is provided. The point 20 formed where the edges 17 and 19 meet, is in alinement with the end of the tongue and the tongues 70 being spaced apart, the edge 17 of the tongue 16 co-operates with the inclined edge 12 of the tongue 10 to form a space between them of the same shape as the tongue 10.

In forming my improved joint I have also 75 constructed the tongues so that the point 21 where the sides 14 and 15 of the tongue 13 meet, will be opposite the point 22 where the sides 18 and 19 of the tongue 16 meet. This formation and arrangement of the 80 tongues as above described is for the purpose of providing a construction which will interlock adjacent pieces as shown in Fig. 3, and is particularly adapted to use in the construction of split water closet seats since 85 the interlocking feature of the tongues 10 and the closely engaging contact of the tongues 13 and 16, will produce a joint which is strong, in that it prevents the pieces pulling apart as well as prevents them 90 warping or bending with relation to one another. In addition to this the close contact of the various tongues produces a thoroughly sanitary construction, in that it affords no possible crevice for the germination of vermin. 95

Another feature of importance is the ease with which the tongues may be formed simultaneously on both of the pieces to be joined. This is more clearly shown in Fig. 100 4 in which two of the pieces to be joined, have had the tongues formed simultaneously on both of them. This feature permits the tongues to be formed in one half the time which would ordinarily be taken to form 105 them separately as in other joint constructions.

In assembling the pieces forming the seat, the pieces 4, 5 and 6 are permanently joined by gluing them together as the pieces are 110 slipped one within the other. The front piece 7 is then brought into spaced position

with relation to the joined pieces 4, 5 and 6, and the locking blocks are gradually forced into position as shown in Fig. 2 until the entire seat has been built up to the form 5 shown in Fig. 1. In this rough condition the seat is ready for finishing. During the assembling operation the several pieces are drawn together to produce an absolutely solid construction in which there is no possibility 10 of the formation of any loose joints which would destroy the strength of the seat and permit of the entrance of water which would warp the seat. In addition to this the close contacting construction of the joints positively prevents the entrance of and germination of vermin and bacteria 15 which would render the seat unsanitary.

Having thus described my invention, what I claim is:

20 A joint construction for securing adjacent members together, comprising an undercut tongue, a pointed tongue located adjacent to the undercut tongue, having an inclined

edge and a straight edge forming an extension of one face of the member, and a second pointed tongue spaced from the undercut tongue, having an inclined edge parallel to the inclined edge of the first mentioned pointed tongue and forming an extension of the opposite face of the member, the space 25 between the undercut tongue and the second mentioned pointed tongue being adapted to receive the undercut tongue of the co-operating member, and the inclined edges of the first and second mentioned pointed 30 tongues being adapted to coöperate respectively with the inclined edges of the second and first mentioned tongues of the co-operating member.

In testimony whereof, I have hereunto 35 subscribed my name this 29th day of April, 1915.

JAMES A. BROWNFIELD.
